UNITED STATES PATENT OFFICE.

JOHN SELLERS BANCROFT, OF PHILADELPHIA, PENNSYLVANIA, ASSIGNOR
TO WILLIAM SELLERS AND COMPANY, INCORPORATED, A CORPORATION
OF PENNSYLVANIA.

TOOL-GRINDING MACHINE.

SPECIFICATION forming part of Letters Patent No. 734,799, dated July 28, 1903.

Application filed April 11, 1903. Serial No. 152,129. (No model.)

To all whom it may concern:

Be it known that I, JOHN SELLERS BANCROFT, a citizen of the United States, residing at Philadelphia, county of Philadelphia, and State of Pennsylvania, have invented a new and useful Improvement in Tool-Grinding Machines, of which the following is a full, clear, and exact description, reference being had to the accompanying drawings, which form a part of this specification.

With machines for grinding the faces, and thus forming the faces, of cutting-tools used on machines it has been customary to arrange the vertical slide-rest so that it may be moved up and down in a vertical line parallel to the plane of rotation of the grinding-wheel. The operative means used for moving this slide-rest up and down was a hand-lever operated by the hand of the workman. In the general run of cutting-tools of moderate weight and in which the amount of grinding required is comparatively slight this arrangement is entirely satisfactory, and, in fact, possesses certain advantages, because the workman can readily and instinctively produce just sufficient motion to make contact between the tool and grinding-wheel to cover the face of the former, and thus use only as much of the entire motion of the vertical slide as is necessary. When, however, very large and heavy tools are to be ground or when the amount to be removed is considerable, the labor of moving the tool up and down in contact with the grinding-wheel has become too great to be readily performed by the hand.

One of the objects of my invention is to provide mechanism whereby the vertical slide-rest shall be moved up and down by power mechanism.

Another object is to so adjust the power mechanism as to provide for only such length of movement of the power mechanism, and thus the vertical slide-rest, as may be necessary to do the work required in each case as it arises.

It is a further object of my invention to provide a hand mechanism for moving the vertical slide up and down and to provide means whereby the motion can be changed from hand to power quickly, readily, and with

certainty, and so that both the power and hand mechanism cannot be in operation at the same time.

Speaking generally, I use a plate having a vibratory motion of fixed extent, and I provide a connection between this plate and the vertical slide-rest which will cause the vertical slide-rest to move up and down with the vibrations of the plate. At the same time this connection may be adjusted in relation to the axis upon which the plate vibrates so that the motion given to the slide-rest, and thus the tool being ground, may vary in extent from nothing to the maximum required. Speaking more specifically, I accomplish this last-mentioned purpose or object by adjusting the pin forming the connection between the plate and connecting-rod in relation to the axis of vibration of the plate so that the connecting-rod on this pin will give motion to the tool being ground in extent varying from nothing to the maximum required, the adjustment of the pin being accomplished by means of a block upon an arm hinged to the plate at a point coinciding with the axis of the pin when at the position of maximum motion, so that as the block is moved in the vibration or amount of motion will be diminished, but will remain symmetrical on both sides of the line connecting the hinged point of arm with the axis of vibration of the plate so long as the arm is parallel with this line; but if the arm is adjusted about the hinge-joint and is turned on the plate at an angle with the arm, then the position of the motion will be raised or lowered. I also arrange a guard for the purpose of limiting the amount of adjustment of the arm upon its hinge, according to the distance of the axis of the connecting-rod pin from the axis of vibration of plate, so that with any given amount of motion for the pin this motion cannot extend above nor below a certain fixed point determined by practical requirements. Further, the arrangement is such that as this motion diminishes by the adjustment of the pin nearer to the axis of vibration of plate the adjustment of the arm is restricted by the guard until the guard prevents any adjustment of the latter when the axis of the pin coincides with the axis of

vibration. I also provide mechanism for changing from power movement to hand movement, and vice versa, in such a manner that the one cannot possibly be connected 5 until after the other is disconnected.

In the drawings, Figure 1 represents an elevation of the tool-grinding machine with my improved device attached. Fig. 2 is a plan of Fig. 1. Fig. 3 is an enlarged elevation of the driving-pulley, crank, and rock-arm. Fig. 4 is an elevation of the vibrating plate, adjustable arm and slide, and end of the connecting-rod; Fig. 5, an underneath view of the same. Fig. 6 is a transverse section of the same, taken on the line *a b* of Fig. 4. Fig. 7 is a plan view showing a horizontal section on the line *c d* of Fig. 1 and showing the hand-lever and lower rock-arm and the means for connecting and disconnecting the 10 hand and power motions. Fig. 8 is a front elevation, and Fig. 9, a side elevation, of the same; and Fig. 10 is a vertical section on the line *e f* of Fig. 2. Fig. 11 is a view of modified form of locking mechanism.

25 A is the grinding-wheel, and B the chuck for holding the tool to be ground. The chuck B can be rotated through any required angle and clamped, and can be adjusted by means of the slide-rests C and D in two directions, 30 one parallel and the other perpendicular to the vertical tangent plane of the grinding-surface of the wheel A. The tool is clamped in the chuck and the latter rotated so as to bring the face to be ground into a vertical 35 plane at the desired angle with its face. This face is then brought into contact with the wheel A by means of the slide-rests C and D, which are mounted on top of the drum or vertical slide-rest E, which has a motion up 40 and down of sufficient extent to insure that the largest tool-surface will completely pass the line of contact with the grinding-wheel A. The required length of this vertical motion must be varied, because the several 45 faces of the same tool and the faces of different tools are not of the same length, and as these faces may not be symmetrical about the axis of the chuck B the total motion must be still further lengthened in order to reach 50 the ends of such faces as extend much above or below this axis.

The vertical slide-rest E is capable of sufficient motion to grind the highest and lowest faces, but as this may be short it is desirable 55 that the motion be not much longer, but adjustable up and down to suit the position of the tool-face in relation to the axis of the chuck B.

The vertical slide-rest E, (see Figs. 1, 2, 7, 60 and 10), carrying the tool-holder, is provided with a pin T, coupled to the link U, which is connected at its upper end to the lever V, fastened to the rock-shaft W. The hand-lever X works freely on the shaft W, as does 65 also the lever Y. The lever Z is fastened to the rock-shaft W, and consequently any motion that the lever Z receives will be trans-

mitted through rock-shaft W, the lever V, link U, and pin T to cause the movement of the vertical slide-rest or drum E. The levers X, Y, and Z have each a slot *g* of the same shape and so located that when the levers are all in their central position these slots will coincide. At the center of the slot in the lever Z is hinged a bolt *h* in such manner that when swung in one direction it enters the slot in lever Y, and thus couples the levers Y and Z together, and any motion given to lever Y is imparted to lever Z. When the bolt *h* is swung in the other direction, it enters the slot in the lever X and connects the lever X and the lever Z together and any motion given to lever X is transmitted through lever Z. As may be seen, also by this arrangement, it is impossible for both 85 levers X and Y to be at the same time coupled to lever Z. In Fig. 11 I have shown an alternative construction to that just described. In this construction Z' is a modification of lever Z and *h*' is a sliding bolt to 90 take the place of swinging bolt *h*. This sliding bolt *h*' is either the same or less length than the slot in lever Z', which it fits, and consequently its end cannot enter the slot in either lever X or Y until its other end is entirely out of the slot in the other. 95

To the lever Y is connected the lower end of the connecting-rod S. The upper end of this connecting-rod S is connected to a pin R, carried by the block P. This block P is 100 slidably connected to the arm M and may be fixedly attached thereto at any point through the medium of the clamping-screw Q. The arm M has the fulcrum-pin N fitting a hole in the vibrating plate L. The plate L has 105 its edge *a* formed in the arc of a circle having the axis of the fulcrum-pin N as its center. The arm M has at one end a portion fitted to this arc and carries a clamp T' for retaining it at any point on this arc. 110

K is a shaft on which the plate L is fastened. On the other end of the shaft the lever J is fastened.

I is the connecting-rod connecting the lever J with the crank H upon the shaft G. Upon 115 the shaft G is the driving-pulley F. The radius of the lever J being greater than that of the crank H the former receives a vibratory motion from the rotation of the latter. This vibratory motion is transmitted through shaft 120 K to the vibratory plate L, giving through arm M and pin R an up-and-down motion to the connecting-rod S, which when the lever Y is connected to the lever Z is transmitted to and causes a corresponding up-and-down 125 movement to the vertical slide-rest. By moving the block P along the arm M the movement of the connecting-rod S may be varied from maximum vibratory motion with pin R near the center of the pin N to the position 130 of no vibration where the center of the pin R coincides with the center of the shaft K. When the arm M is, as shown in Fig. 4, parallel with a line passing through the hinged

point of the arm N, the axis of vibration K of plate L, and the pin R for all the different positions of the block upon the arm M the amount of motion will remain symmetrical on both sides of a line connecting the hinged point with the axis of vibration. If, however, the arm is adjusted by the clamp T', so that it is at an angle with the line connecting the hinged point and the shaft K, then the position of the motion of pin R will be raised and lowered in relation to its original position, according as arm M has been swung up or swung down and to the extent the arm M has been so swung. It is advisable, however, to provide means which will prevent the extremes of maximum motion to be imparted to the tool-holding chuck being overrun. It is also desirable that when this motion is reduced to zero the tool should be in its central position—*i. e.*, the arm M brought to its central position and the pin R coincident with the axis of shaft K. In order to accomplish this result, I provide the following mechanism: Upon the plate L, I secure a guard-rail l, and upon the block P, I secure a pin p. This rail is so shaped that the pin p in any position of the block P, when the arm M is swung on the fulcrum-pin N, above or below the central position, will strike guard l within the extremes of the maximum motion of the tool-holding chuck. The upper and lower portions of rail l also converge toward each other, so that at a point in line with the axis of shaft K the distance between them is such as to allow no substantial movement of pin p, and the position is such that when the pin p is at that point the pin R coincides with the axis of the shaft K. Thus to bring the block P to zero position the arm M must be moved central and the pin R coinciding with the axis of shaft K, thus bringing the tool central when the block is brought to the zero position.

Having now fully described my invention, what I claim, and desire to protect by Letters Patent, is—

1. In a tool-grinding machine, in combination, with the vertically-movable slide-rest, of a vibratory plate, a device connected to said plate, so as to vary its lateral position with reference to the axis of vibration of said plate, mechanism to elevate said vertically-movable slide-rest and connection between said device and said mechanism.
2. In a tool-grinding machine, in combination, with the vertically-movable slide-rest, of a vibratory plate, a device connected to said plate so as to vary its lateral and vertical position with reference to the axis of vibration of said plate, mechanism to elevate said vertically-movable slide-rest and connection between said device and said mechanism.
3. In a tool-grinding machine, in combination, with the vertically-movable slide-rest, of a vibratory plate, a device connected to said plate so as to vary its lateral and verti-

cal position with reference to the axis of vibration of said plate, mechanism to elevate said vertically-movable slide-rest and connection between said device and said mechanism, and a guard for limiting the vertical movement of said device.

4. In a tool-grinding machine, in combination, with the vertically-movable slide-rest, of a vibratory plate, an arm secured to said plate, a block movable along said arm, a connecting-rod secured to said arm and connection between said rod and the vertically-movable slide-rest.

5. In a tool-grinding machine, in combination, with the vertically-movable slide-rest, of a vibratory plate, an arm secured to said plate, a block movable along said arm, a connecting-rod secured to said arm and connection between said rod and the vertically-movable slide-rest, the point of connection of said rod to the block being such that when the block is in vertical alinement with the axis of said plate, the connecting-point of said rod and block is coincident with the axis of vibration of the plate.

6. In a tool-grinding machine, in combination, with the vertically-movable slide-rest, of a vibratory plate, an arm pivoted to said plate, a block movable along said arm, a connecting-rod secured to said arm, connection between said rod and the vertically-movable slide-rest, and means to limit the movement of the arm upon the pivot.

7. In a tool-grinding machine, in combination, with the vertically-movable slide-rest, of a vibratory plate, an arm pivoted to said plate, a block movable along said arm, a connecting-rod secured to said arm and connection between said rod and the vertically-movable slide-rest, and means to bring the arm and block into such position that the point of connection of the block and connecting-rod is coincident with the axis of the plate.

8. In a tool-grinding machine, in combination, a vibratory plate, an arm connected to said plate, and a block slidably mounted upon said arm.

9. In a tool-grinding machine, in combination, a vibratory plate, an arm pivoted to said plate, the plate having an edge curved from a center coincident with the pivot-point of the arm, and a clamp for clamping the arm to the plate at the curved portion thereof.

10. In a tool-grinding machine, in combination, a vibratory plate, an arm pivoted to said plate, a block slidably mounted upon said arm, and a device for limiting the movement of the arm upon its pivot.

11. In a tool-grinding machine, in combination, a vibratory plate, an arm pivoted to said plate, a block slidably mounted upon said arm, and a device adapted, when the block is in vertical alinement with the axis of the plate, to compel the arm to assume a fixed position with reference to said axis.

12. In a tool-grinding machine, in combination, a vibratory plate, an arm pivoted to

said plate, a block slidably mounted upon said arm, a pin secured to said block and a rail secured to said plate above and below said block to limit the movement of the arm upon 5 the pivot.

13. In a tool-grinding machine, in combination, a vibratory plate, an arm pivoted to said plate, a block slidably mounted upon said arm, a pin secured to said block and a 10 stop secured to said plate in vertical alinement with the axis of said plate to prevent the movement of the arm upon the pivot when the block is in vertical alinement with said axis.

14. In a tool-grinding machine, in combination, a vibratory plate, an arm pivoted to said plate, a block slidably mounted upon said arm, a pin secured to said block and a rail secured to said plate above and below 20 said block, said rails converging together to a point in vertical alinement with the axis of the plate.

15. In a machine of the character described, in combination, with a vertically-movable

slide-rest, a lever and connection between 25 said lever and vertically-movable slide-rest, of independent operating-levers and a locking device carried by the first-named lever adapted to engage either of the last-named levers.

16. In a machine of the character described, in combination, with a vertically-movable slide-rest, a lever having a slot and connection between said lever and vertically-movable slide-rest, of two independent levers 35 each having slots, the slots of the first-mentioned lever and last-mentioned levers being adapted to be brought in alinement and a locking-pin pivoted in the slot of the last-mentioned lever.

In testimony of which invention I have hereunto set my hand at Philadelphia on this 4th day of April, 1903.

JOHN SELLERS BANCROFT.
